UNITED STATES PATENT OFFICE.

HARRIS D. BLOOMENTHAL, OF SUPERIOR, WISCONSIN.

GARMENT.

1,246,044.

Specification of Letters Patent. Patented Nov. 13, 1917.

Application filed April 7, 1917. Serial No. 160,554.

To all whom it may concern:

Be it known that I, HARRIS D. BLOOMENTHAL, citizen of the United States, residing at Superior, in the county of Douglas and 5 State of Minnesota, have invented certain new and useful Improvements in Garments, of which the following is a specification, reference being had therein to the accompanying drawing.

10 This invention relates to garments such as are commonly known as overalls, and designed to be slipped on and off over other clothes worn more continuously.

15 One object of the invention is to provide convenient means for holding the overalls about the body of the wearer.

Another object is to provide such overalls having a detachable bib which may or may not be used therewith.

20 Still another object is to provide a novel means of supporting the upper end of the bib about the neck of the wearer.

In the accompanying drawings forming 25 part of this application and in which like reference characters indicate like parts:—

Figure 1, is a perspective view of a fragmental portion of a pair of overalls with the improved bib attached, and

Fig. 2, is a similar view with the bib removed.

1 represents the front of the waist portion of the overalls, 2 the back thereof and 3 the bib. The front waist band is provided with five external buttons 4, to which the bib may 35 be buttoned, as it is provided with suitable button holes 5 for such purpose.

When the bib is removed, one or more of the buttons 4 may be buttoned into the front straps of the regular suspenders, if used by 40 the wearer of the overalls, but the belt, hereinafter described, will ordinarily form adequate means of support and especially so inasmuch as a very much larger number, than heretofore, of working men have come to 45 using trousers and overalls without suspenders.

The waist band 6, of the back portion 2, is formed of a double wall and hollow throughout, providing a suitable casing 50 through which the belt 7 passes, forming a sort of draw string to the waist band 6.

One end of the belt is permanently fastened, as at 8, to one corner of the front waist portion and is designed to enter the 55 open end of the casing 6, upon the adjacent

corner of the V-shaped opening 9, one of which occurs upon each side of the waist of the overalls.

The free end of the belt protrudes at all times from the opposite open end of the casing and is of a relative size to freely pass therethrough.

On the corner 11, of the front portion of the waist, is permanently fixed a short piece of belt 12, which is designed to be tied to the free end of the belt 7 across the top of the opening 10, for holding the band of the overalls tightly about the waist of the wearer.

It is evident that these ends of the belt 70 may be drawn to a tension to suit the wearer, and the tying quickly and easily accomplished.

As an additional means of support for the back of the trousers, I provide two loops 75 13—13 stitched to the inside of the waist band and which may, if desired, be attached to the suspenders of the wearer, and similar loops 19—19 may be stitched to the front portion of the waist band, for a like purpose. 80

The belt and loops I prefer to form of the same material as that of which the overalls are made, but they may be of other material if desired.

The front waist band is preferably continuous from side to side, there being no break above the ordinary opening 14, thus dispensing with the necessity of buttons longitudinally the opening 14, as are usually employed.

90 The bib 3, is preferably formed with the sides thereof converging upwardly, and at one corner 15, of the upper end thereof, a piece of belting 16, similar to the belt 7, is permanently attached, the free end of which is designed to engage a buckle 17, removably attached to the button 18, attached to the opposite corner of the upper end of the bib.

It is readily seen that the loop thus formed by the belting 16 may be readily 100 slipped over the head of the wearer without in any other manner adjusting same.

While I have shown the bib as detachably fixed to the trousers, it is evident that it may be permanently fixed thereto if desired.

105 From the foregoing, it is evident that I have devised a novel combination garment and one having many commendable characteristics.

Having thus described my invention what 110

I claim and desire to secure by Letters Patent is:

A pair of overalls, having in combination 5
V-shaped openings in either side of the waist
thereof dividing the waist band into two
continuous halves, a detachable bib buttoned
to the front half of the waist band, said bib
having independent supporting means at
the upper end thereof, the back half of the
10 waist band formed into a hollow casing, up-
wardly extending loops permanently fixed
to the front of the hollow casing, similar
loops permanently fixed to the inside of the
front half of the waist band, a belt perma-
15 nently fixed to one corner of the front half

of the waist band and passing through the
casing in the back half and out of the oppo-
site end thereof, a shorter piece of belt per-
manently fixed to the opposite corner of the
front half and engageable by tying with the 20
free end of the first mentioned belt and an
opening in the front of the garment below
the continuous front half of the waist band,
substantially as described.

In testimony whereof I hereunto affix my 25
signature in the presence of two witnesses.

HARRIS D. BLOOMENTHAL.

Witnesses:

O. MARCUS,
L. LASKY.
